SANDING MACHINE

Edmund C. Clarke, Jacksonville, Fla.

Application June 26, 1939, Serial No. 281,239

4 Claims. (Cl. 51—135)

This invention relates to sanding machines and more particularly to sanding machines of the continuous belt type.

One object of this invention is to provide a sanding machine of the continuous belt type.

Another object is to provide a continuous belt sanding machine so arranged that the belt may be readily changed.

A further object is to provide a sanding machine of the continuous belt type, which may be readily adjusted with respect to a working plane.

Yet, a further object is to provide a sanding machine of the endless belt type, wherein the motor drive is always connected to the sanding belt, irrespective of the adjustment of the latter.

Other objects and advantages of this invention will appear from the following description taken in connection with the accompanying drawings.

In the drawings, wherein like reference characters indicate corresponding parts in the various figures:

Figure 1 is a front elevation of a sanding machine of the endless belt type, showing a preferred embodiment incorporating features of the present inventive concept;

Figure 2 is a plan view of the device in Figure 1;

Figure 3 is a partial vertical cross-section substantially on the line 3—3 of Figure 1, showing the power drive;

Figure 4 is a view substantially along the line 4—4 in Figure 1, showing the opposite end support for the continuous belt;

Figure 5 is an enlarged detail transverse section along the line 5—5 in Figures 1 and 2;

Figure 6 is an enlarged detail substantially on the line 6—6 of Figures 1 and 3.

Figure 7 is a partial plan view showing the adjustable arrangement of the pulley 21.

Considering the drawings in greater detail, the device includes a table 10 arranged to support the entire apparatus. At the opposite ends of the table are mounted supporting brackets 11 and 12, which are substantially H-shaped in transverse cross-section, as clearly seen in Figure 6, and which are rigidly secured to the table by appropriate fastening means 13. Each bracket carries at its outer end a bearing structure 14 arranged to provide a pivotal mounting means for the opposite ends of the endless belt.

Intermediate the supports is arranged a table 15, which is adjustable with respect to the support 10, and which is of sufficient width to serve both as a flat surface for the upper moving strand 16 of the belt 17, as well as a supporting surface

for articles being sanded. This table has an enlarged boss 18, from which extends downwardly a leg 19, arranged to adjustably support the table with respect to the mechanism. The endless belt 17 extends about a driving pulley 20 pivotally mounted upon the bearing 14 at the power end of the device, and upon a similarly arranged pulley 21 mounted at the opposite end of the device. The belt 17 has its upper strand 16 extending between these pulleys as well as the lower strand or section 22, which normally extends a short distance above the supporting table 10.

As viewed in Figure 4, the left-hand pulley 21 is rotatably mounted upon a shaft 23, which in turn, is secured within a bearing 24. The bearing is secured upon an outwardly extending arm 25 of a cup-shaped bearing and supporting element 26. The latter encompasses the bearing 14 and is secured thereupon by pin 27 and its securing means 28, for oscillating or rotary motion.

A similar mechanism is mounted at the opposite end of the table 10 and comprises an oscillatable arm 29 secured by cup-shaped bearing member 30 upon the bearing 14, and secured thereto by the headed pin 27 and securing means 28. The arm 29 in this case carries a similar bearing 24'.

In order to keep these arms in appropriate position and at the same time allowing for adjustable positioning of the endless sanding belt, a double ended yoke or link 31 is secured with relation to the shafts 23 and 23' of the sanding machine. The link is bifurcated at each end, and as clearly observed in Figures 2 and 6, the bifurcated yoke portions 32 and 33 each have a bearing element 34 and 35 concentric with axis of shaft 23. The opposite end of the yoke is bifurcated with arms 36 and 37, similarly supporting bearing elements which are concentric with the shaft 23'. In view of this arrangement, it will be appreciated that movement of the shaft 23' about the center 27 of bracket 12 will also result in a similar movement of shaft 23 about the axis 27 of bracket 11. As a result of this arrangement, it will be observed that the endless belt may be raised and lowered so that its upper and lower strands move parallel away from or toward the table 10.

The table 15 previously described has its leg 19 passing through an aperture in the enlarged boss 38, carried by the yoke 31. A set-screw 39 locks the leg 19 so as to maintain the belt 17 in definite relationship to the table.

The power drive for the sanding mechanism comprises a motor 40, mounted upon a shelf 41,

which is in turn, secured upon the bearing shell 30. A change speed pulley 42 has an endless belt 43 carried thereon, and arranged to engage with a driving pulley 44, which latter turns on shaft 5 23' and serves as the power drive for the sanding mechanism by way of pulley 20.

As a result of the construction thus far described, whenever the sanding belt is raised or lowered with respect to the table, a motion of the 10 axis 23 about its support axis 27 will take place, with the axis 23' moving in a similar manner. The motor 40 will also move about the pivot 27 of bracket 12 in a clock-wise direction at the same time as does the shaft 23'.

15 For the purpose of accomplishing this movement in a controlled and regulated manner, and at the same time rendering the mechanism suitable for locking or holding the sander in definite spacing with regard to the support 10, a vernier 20 mechanism is provided.

This latter mechanism includes a U-shaped element 45 pivotally supported at 46 upon the bracket 12. A screw-threaded rod 47 carries a hand-wheel 48 at its outer end and is rotatably 25 supported in the U-shaped member 45 and limited as to axial movement thereof by means of collars 49. This shaft passes through a screw-threaded aperture 50 in the shaft 23'. The result obtained by this construction is that the turning of the 30 hand-wheel in a clock-wise or counterclock-wise direction results in a movement of the shaft 23' to a determinate position removed from the position shown in Figure 1, and comprising an arc with axis 27 as a center.

35 In order to limit axial movement of the shaft 23' a set-screw 51 is arranged to ride within the slot 52 cut in this shaft, as clearly observed in Figure 6. This will maintain a driving end of the sanding belt in fixed relation with respect to the 40 remaining parts of the apparatus, it being observed that the pulley 20 and pulley 44 are secured to a housing which is freely rotatable on the shaft 23, the latter serving as a bearing support for these elements.

45 In order to render the belt readily replaceable, the pulley 21 is adjustable. The bearing device 52 secured to a rod 53, which latter has the hand-wheel 54, provides the means for shifting the axis of the pulley 21 so that the belt may be replaced. The rod 53 is threaded and rides through a 50 threaded boss 55 carried upon the yoke 31.

This arrangement is primarily to make the belt track evenly on both pulleys. It will also be

noted that the table 15 serves to tension the sanding belt.

Although a preferred embodiment of this invention is illustrated and described, variations within the true spirit and scope of same are to 5 be determined by the appended claims.

What I claim is:

1. A sanding machine comprising a table base, two pedestals fixed on said base, each of said pedestals having a bearing, a bracket oscillatably 10 mounted on each pedestal bearing, a shaft carried by each of said brackets parallel with each other and to the table base, pulleys mounted on said shafts, an abrasive belt mounted on the pulleys, a connecting rod pivotally connected at each 15 end to one of said shafts and means associated with one pedestal and its associated shaft to angularly adjust said shaft with respect to the pedestal bearing whereby the space between the lower reach of the abrasive belt and the table 20 base can be regulated.

2. The structure of claim 1 in which one of the brackets is formed with a motor seat, a motor on said seat and power transmission means between the motor and the pulley carried by the 25 same bracket.

3. The structure of claim 1 in which the pedestal bearings are formed as drums and the brackets have cup-like bearings to embrace said drums whereby oscillation of the brackets is permitted. 30

4. A sanding machine comprising a table base, two arcuate pedestals mounted on the base, each of said pedestals formed with an overhanging drum bearing, a bracket for each pedestal, each bracket formed with a cup-like part to seat on 35 the drum and having a depending arm angularly disposed toward the pedestal, a shaft carried by the depending arm of each bracket and extending under and clear of the pedestal, pulleys on each shaft, an abrasive belt mounted on said pulleys, said belt and pulleys mounted clear of the pedestals, a connecting rod having bifurcated ends, said bifurcated ends pivotally engaging the respective shafts and straddling the arms of said brackets under the bearings, a motor mounted on one of 40 said brackets, power transmission means between the motor and the pulley carried by that bracket and means carried by one pedestal whereby the brackets can be angularly adjusted and the space between the lower stretch of the belt and the table 45 base regulated.

EDMUND C. CLARKE.
